ARCHERY BOWSTRING RELEASE AID

Marston E. F. Wigley, Cheektowaga, N.Y., assignor to
C & S Archery Co., Inc., Cheektowaga, N.Y.

Filed May 30, 1974, Ser. No. 474,309

Term of patent 14 years

Int. Cl. D22—01

U.S. Cl. D22—5

Fig. 1.

Fig. 2.

Fig. 3.

Fig. 4.

Fig. 5.

FIG. 1 is a top plan view of an archery bowstring release aid showing my new design;

FIG. 2 is a rear elevational view thereof;

FIG. 3 is a front elevational view thereof;

FIG. 4 is a side elevational view thereof; and

FIG. 5 is an opposite side elevational view thereof.

The non-illustrated bottom plan view is identical to the illustrated top plan view thereof.

I claim:

The ornamental design for an archery bowstring release aid, as shown and described.
